EX
OF 1 1032

Design
Nathaniel Waterman's Towel Stand.
Patented Aug. 3, 1958.

1032.

1

Des 1032

Nathaniel Waterman, of Boston, Mass,
Letters Patent No 1032. Dated Aug. 3, 1858.

The Schedule referred to in these Letters Patent and making part of the same,

To all Persons to whom these Presents shall come:

Be it known that I, Nathaniel — Waterman of Boston, in the County of Suffolk, and State of Massachusetts, have invented or produced a new ornamental design for a Towel Stand, and I do hereby declare the same to be fully represented in the accompanying drawings, of which,

Figure 1. is a perspective view of a towel stand made

100

Res. 1032

in accordance with the said design.

Figure 2. is an end view, and

Figure 3. a side elevation of it.

In carrying out the design in question, I employ two round posts, a. a, each being united at its two ends by connections f. f. two curved wires or bars, b. c. whose corners are arcs of circles and are arranged in opposite directions. Their ends terminate in connection balls d. d. and f. f. e. e. as shown in the drawings. The balls d. d. serve to connect the horizontal rods or bars, g. g. to the curved rods, c. c.

Another rod h. extends from one vertical part to the other and is connected to them by the connections i. i. formed as shown in the drawings.

What I claim is the design or configuration of the towel stand as above described and is exhibited in the accompanying

end ing drawings.

S.M.B.

In testimony whereof I have hereunto set my signature.

Witnesses.

R. H. Eddy.

J. P. Hale Jr.
